UNITED STATES PATENT OFFICE.

CORRIE F. RUDOLPH, OF WASHINGTON, DISTRICT OF COLUMBIA.

COMBINATION FAUCET AND DRINKING-FOUNTAIN.

1,240,260.

Specification of Letters Patent. Patented Sept. 18, 1917.

Application filed February 7, 1916. Serial No. 76,617.

To all whom it may concern:

Be it known that I, CORRIE F. RUDOLPH, a citizen of the United States of America, residing at Washington, District of Columbia, have invented certain new and useful Improvements in Combination Faucets and Drinking-Fountains, of which the following is a specification.

This invention relates to a combined 10 faucet and drinking fountain.

The primary object of the invention is to provide a faucet in which is mounted a handle operated valve, the stem of said valve being provided with a mouth piece to 15 serve as a drinking fountain when the handle is moved in one direction, while the valve is provided with a port which when the handle is moved in the opposite direction will register with the water passage 20 within the faucet so that the faucet may be used in the usual manner.

Another object of the invention is to provide the valve stem with means for regulating the flow of water through the valve stem 25 to the mouth piece, said means also serving to connect the handle which controls the movement of the valve stem with the same.

Another object of the invention is to provide the valve with ports, one of which 30 is so arranged that it communicates with the water passage in the valve stem, and when the valve stem has been turned to a position which prevents water from entering said ports any fluid which is within the water 35 passage in the valve stem may be drained therefrom.

Another object of the invention is to provide the faucet with a frame in which may be displayed advertising matter bearing 40 suitable indicia indicating the position to which the handle should be moved to control the flow of water through the faucet, the nozzle thereon or the fountain.

With these and other ends in view which 45 will readily appear as the nature of the invention is better understood, the same consists in the improved construction and novel arrangement and combination of parts which will hereinafter be fully described 50 and particularly pointed out in the claims.

In the accompanying drawings has been 55 illustrated a simple and preferred form of the invention, it being, however, understood that no limitation is necessarily made to the precise details of construction therein shown, but that changes, alterations and

modifications within the scope of the claims may be resorted to when desired.

In the drawings,—

Figure 1 is a vertical longitudinal sectional view through a faucet constructed in accordance with the invention, the valve and valve stem included therein being shown partly in elevation.

Fig. 2 is a top plan view of the faucet. 65

Fig. 3 is a sectional view on the line 3—3 of Fig. 1.

Fig. 4 is a horizontal transverse sectional view through the valve and valve chamber showing the same removed from the faucet 70 with the valve moved to a position in which the fountain port registers with an outlet opening in the valve chamber so that fluid from the water passage in the valve stem may be drained therefrom. 75

Fig. 5 is a view similar to Fig. 4, showing the valve moved to a position in which the fountain port registers with an inlet opening in the valve chamber to establish communication between the water passage in the 80 valve stem and faucet.

Fig. 6 is a view similar to Fig. 4, showing the valve moved to a position in which the faucet port is closed.

Fig. 7 is a view similar to Fig. 6, showing 85 the valve moved to a position in which the faucet port therein establishes communication between the faucet inlet and outlet openings in the valve chamber.

Fig. 8 is a side elevation of the valve 90 chamber.

Like characters of reference denote corresponding parts throughout the several figures.

Referring now to the drawing in detail, 95 the numeral 1 designates the faucet body having at one end a nozzle 2 and at its opposite end an enlarged and threaded portion 2' for connection with the water supply pipe and provided throughout its length with a 100 water passageway 3, said body being provided between its ends with an enlargement extending above and below the water passageway 3 to provide a vertically extending bore 5. The enlarged portion of the body 105 above the water passageway 3 is provided with a lug or stop shoulder 6.

A cylindrical sleeve 7 is secured within the bore 5 in any suitable manner, said sleeve having its inner peripheral wall tapered to 110 provide a valve seat 8. A tapered valve 9 is mounted to turn in said seat and is pro-

vided with a faucet port 10 adapted to register with faucet inlet and outlet openings 11 and 12 arranged at diametrically opposite points in the portion of the sleeve with 5 in the water passage 3.

The valve 9 is further provided with a fountain port 13 adapted to register with a fountain inlet opening 14 in the sleeve 7 and having a reduced and angularly ar- 10 ranged portion for registration with a fountain outlet opening 15 in the sleeve 7 and diametrically opposite the inlet opening 14. A valve stem 8 extends upwardly from the valve 9 above the sleeve 7 and is provided 15 with a longitudinally extending and inclined water passageway 16 communicating at its lower end with the fountain port 13 at its intersection with the reduced portion thereof, while the upper end of said passageway 20 is received by the reduced end of a mouth piece 17 removably connected with the valve stem by means of a set screw 18 and having communication with the water passageway 16. A handle 19 is provided at one end 25 with a collar 20 receiving the valve stem 8, said collar being provided with a channel 21 and on its under face with a semi-circular-shaped flange 22, the ends of which are adapted to alternately contact with the lug 30 or stop shoulder 6 when the valve stem is turned by means of the handle to cause the ports within the valve to register with the water passageway in the faucet body.

The valve stem 8 is provided between its 35 ends with a transversely extending and threaded opening 23 in which is received the reduced and threaded portion of a flow-controlling member 24, the head of said member being located within the channel 21 40 and grooved to receive a suitable key or other instrument by means of which the member may be adjusted to cause the reduced portion thereof to extend within the water passageway 16 to control the flow of 45 water through said passageway and above the mouth piece 17 connected with the valve stem.

An inclined frame 25 is formed integral with the faucet body in the rear of the handle 19, said frame being flanged to receive a magnifying glass 24 beneath which may be displayed advertising matter bearing suitable indicia indicating the direction in which the handle should be moved to enable 55 water to pass from the supply pipe through the fountain or through the nozzle of the faucet, as the occasion may require, said advertising matter being secured within the frame in any suitable manner.

60 When the faucet has been connected with a water supply pipe a person desiring to fill a glass or cup with water from the faucet in the usual manner turns the handle in the direction indicated by the printed matter 65 within the frame until one end of the flange

22 contacts with the lug 6 in which position the faucet port 10 will be in registration with the inlet and outlet openings 11 and 12 in the sleeve 7. When the receptacle has been filled the handle is moved to a position 70 as indicated by the printed matter to close the said ports and at which time the reduced portion of the fountain inlet port will be in registration with the fountain outlet opening 15 in the sleeve 7, so that the fluid 75 which remains in the water passageway 16 in the valve stem may be drained therefrom.

When it is desired to use the fountain the handle is moved in the direction indicated by the printed matter in the frame until the 80 opposite end of the flange 22 contacts with the lug 6 at which time the reduced portion of the fountain inlet passage will be closed by the sleeve 7 and the other end of said passage registering with the fountain inlet 85 opening in the sleeve, so that water may pass from the water passage 3 in the faucet body through the channel 16 in the valve stem and overflow the mouth piece 17.

From the foregoing description, it will be 90 seen that a combined faucet and drinking fountain has been provided in which a valve is provided for directing fluid through the fountain or nozzle on the faucet, said valve being provided with means for draining 95 fluid from the fountain when the supply of water thereto has been discontinued by means of the valve, thereby providing a combined drinking fountain and faucet which is inexpensive of manufacture, simple 100 in construction and highly efficient in use.

Having thus described the invention, what is claimed as new, is:

1. In a device of the class described, a faucet body having a valve chamber therein, a valve casing in said chamber having spaced pairs of upper and lower openings therein aligning with the passage of the faucet body, a valve mounted to turn in said casing and having a passage extending longitudinally thereof and provided at its lower end with a pair of branches arranged at right angles thereto and diverging outwardly from the lower end of said passage to the periphery of the valve, one of said branches being adapted to normally register with one of the openings in the uppermost pair of openings in the valve casing, the other of said branches being adapted to register with the other opening in the uppermost pair of openings in the valve casing when the valve is partially rotated in one direction, and a second passage in said valve extending transversely thereof adapted to register with the lowermost pair of openings in the valve casing when the valve is partially rotated in the opposite direction.

2. In a device of the class described, a faucet body having a valve chamber therein, a valve casing in said chamber having spaced 130

pairs of upper and lower openings therein alining with the passage of the faucet body, a valve mounted to turn in said casing and having a passage extending longitudinally 5 thereof and provided at its lower end with a pair of branches arranged at right angles thereto and diverging outwardly from the lower end of said passage to the periphery of the valve, one of said branches being 10 adapted to normally register with one of the openings in the uppermost pair of openings in the valve casing, the other of said branches being adapted to register with the other opening in the uppermost pair of openings 15 in the valve casing when the valve is partially rotated in one direction, a second passage in said valve extending transversely thereof adapted to register with the lowermost pair of openings in the valve casing 20 when the valve is partially rotated in the opposite direction, and a cup on said valve

in communication with the upper end of the first mentioned passage.

3. In a device of the class described, a faucet body, a valve mounted to turn in said body and extending above the same, said valve having a passage therein adapted to communicate with the interior of the faucet body, an operating handle for said valve having a collar thereon through which the 25 extending portion of the valve is passed, said collar having an opening therein, and a flow control member on said valve having an end extending within the opening in said collar and its other end extending within 30 the passage in said valve.

In testimony whereof I affix my signature in the presence of two witnesses.

CORRIE F. RUDOLPH.
